Primary Examiner — Katherine Glennon(74) *Attorney, Agent, or Firm* — Donald J. Ranft; Collen(57) **CLAIM**

The ornamental design for a watch, as shown and described.

DESCRIPTION

FIG. 1 is a front right perspective view of a watch showing my new design;

FIG. 2 is a rear right perspective view thereof;

FIG. 3 is a front view thereof;

FIG. 4 is a rear view thereof;

FIG. 5 is a bottom view thereof;

FIG. 6 is a top view thereof;

FIG. 7 is a right side view thereof;

FIG. 8 is a left side view thereof;

FIG. 9 is a front left perspective view thereof; and,

FIG. 10 is a rear left perspective view thereof.

The portions of the watch shown in broken lines form no part of the claimed design.

1 Claim, 10 Drawing Sheets(56)
